UNITED STATES PATENT OFFICE.

JAMES EDWARD SCHOFIELD THORNHILL, OF BESWICK, THOMAS FORKNALL,
OF FAIRFIELD, AND EDWARD THORNHILL, OF ARDWICK, COUNTY OF
LANCASTER, ENGLAND.

RAILWAY-CARRIAGE.

SPECIFICATION forming part of Letters Patent No. 320,601, dated June 23, 1885.

Application filed March 24, 1884. (No model.) Patented in England October 30, 1883, No. 5,144.

To all whom it may concern:

Be it known that we, JAMES EDWARD SCHOFIELD THORNHILL, of Beswick, near Manchester, in the county of Lancaster, England, engineer, THOMAS FORKNALL, of Fairfield, near Manchester, in the county aforesaid, engineer, and EDWARD THORNHILL, of Ardwick, near Manchester, in the county aforesaid, overlooker, have invented certain new and useful improvements in mounting the wheels of railway-carriages and tram-cars, and in the axles of such railway-carriages and tram-cars, of which the following is a specification.

Our invention relates to the construction and arrangement of the axles and bearings of the wheels of railway-carriages and tram-cars; and it consists in arrangements whereby we are enabled to reduce the amount of tractive force required to move such railway-carriages and tram-cars.

In order that our invention may be readily understood, we will proceed to describe the same, reference being made to the drawings hereunto annexed.

Figure 1 is a plan, Fig. 2 a side elevation, and Fig. 3 an end view, of so much of a railway-carriage or tram-car as is requisite to illustrate our invention.

At $a a' a'' a'''$ are axles, fast upon which are mounted wheels $b b' b'' b'''$, respectively. For the present we will assume that the axles $a a' a'' a'''$ terminate at the points $A A' A'' A'''$, respectively, and as the axles $a a' a'' a'''$ and wheels $b b' b'' b'''$ are similar to the axle a and wheel b , respectively, we shall only describe the axle a and wheel b , and to the remaining axles and wheels we shall affix similar letters of reference, with the addition of a distinguishing number attached thereto.

At $c c$ are end pieces made of timber or other suitable material, to which end pieces $c c$, in any convenient manner, are secured other pieces of timber or other suitable material, $d d d$.

Secured to the pieces $d d d$ are plates of metal $e f g h$, upon which are formed projecting parts or horn-plates $e^* f^* g^* h^*$, which act as guides between which the axle boxes $j k$, mounted upon the axle a , may slide. Although

we have shown two plates called "horn-plates," $e f$ or $g h$, for each axle-box j or k , one only of such plates or horn-plates may be employed, if desired; or the plates $e f g h$ may be dispensed with and the axle-boxes $j k$ may be connected to the frame of the railway-carriage or tram-car by means of springs or in any other convenient manner.

The axle-boxes $j k$ are provided with steps l , (one only of which is shown,) which steps are supported upon necks or journals $a^* a^{**}$, formed upon the ends of the axle a , one neck or journal, a^* , being at one side of the wheel b , and the other neck or journal, a^{**} , being at the other side of such wheel b . The axle-boxes $j k$ may support the frame of the railway-carriage or tram-car by means of any ordinary arrangement of spring or springs, one form of such spring being indicated by the dotted lines B.

Upon the axle-boxes $j k$ are projecting parts 70 which act as guides to retain such axle-boxes $j k$ in position when sliding upward and downward upon the guide-plates $e f g h$. The journals $a^* a^{**}$ formed upon the axle a have collars formed at their ends, so that the axle a is 75 prevented from moving longitudinally.

By forming two necks or journals $a^* a^{**}$ upon the axle a , one of such necks being upon one side of the wheel b and the other neck upon the other side of the wheel b , we divide 80 the weight of the railway-carriage or tram-car and its load to be supported by the wheel b between the two necks or journals $a^* a^{**}$.

By dividing the load supported by the wheel b between the two necks or journals $a^* a^{**}$ we are enabled to reduce the diameter on such necks or journals $a^* a^{**}$ without increasing the liability of the axle a to bending or fracture.

By reducing the diameter of the necks or 90 journals of the axles of railway-carriages and tram-cars, as above described, we reduce the friction of such necks or journals upon the steps or bearings within which such necks or journals revolve, and we thus cause a less 95 amount of tractive force to be required to move such railway-carriage or tram-car aforesaid.

In the drawings we have shown a railway-carriage or tram-car having four wheels; but it will be readily understood that a greater number of wheels may be employed, if desired.

5 We have hitherto referred to the axles $a a'$ $a^2 a^3$ as being independent of each other, but we propose in some cases to connect the axles $a a'$ upon one side of the railway-carriage or tram-car to the axles $a' a^3$, respectively, upon 10 the opposite side of such railway-carriage or tram-car, in which case we prolong the axle a to the point C, and form upon the said axle a a collar, n . We prolong the axle a' to the point C, and form or secure thereon a socket, o , 15 within which passes the end p of the axle a . Upon the socket o we form a flange, q . At r is a plate secured to the socket o by means of bolts s . The plate r has a circular opening formed therein, within which the axle 20 a is free to be revolved. The plate r maintains the collar n within the circular recess formed in the socket o , thereby preventing the axles $a a'$ from separating longitudinally. The 25 socket o , bolts s , plate r , and collar n form a coupling which serves to maintain the axles

$a a'$ in a line with each other, while at the same time leaving them free to revolve independently of each other.

We desire it to be understood that we do not confine ourselves to the above-described 30 construction of coupling for connecting the axles, as any suitable arrangement of coupling may be employed.

What we claim as our invention, and desire to secure by Letters Patent, is—

35 The combination, with a railway-carriage or tram-car, of the wheels $b b' b^2 b^3$, the axles $a a'$ $a^2 a^3$, one for each wheel, and each having two journals, the axle-boxes $j k, j' k', j^2 k^2, j^3 k^3$, two for each axle, and the couplings, one between 40 each two axles, which are in line with each other, all substantially as herein described.

JAMES EDWARD SCHOFIELD THORNHILL.

THOMAS FORKNALL.
